UNITED STATES PATENT OFFICE.

CHRISTIAN OLSEN, OF CANTON, MISSISSIPPI.

STATION-INDICATOR.

SPECIFICATION forming part of Letters Patent No. 367,114, dated July 26, 1887.

Application filed March 24, 1887. Serial No. 232,292. (No model.)

To all whom it may concern:

Be it known that I, CHRISTIAN OLSEN, a citizen of the United States, residing at Canton, in the county of Madison and State of Mississippi, have invented a new and useful Improvement in Station-Indicators, of which the following is a specification.

My invention relates to an improved station-indicator, the novelty of which consists in the construction and arrangement of parts, as hereinafter fully described and claimed.

In the drawings hereto annexed, Figure 1 is a perspective view of the device. Fig. 2 is a side view thereof. Fig. 3 is a transverse vertical section on the line $x-x$ of Fig. 2. Fig. 4 is a horizontal section on the line $y-y$ of Fig. 2.

Fig. 5 is a view similar to Fig. 3, with the labels shown therein. Fig. 6 is a detail view of one of the labels.

20 Referring to the drawings, in which similar letters denote corresponding parts in all the figures, A designates the body of the indicator, comprising two sections, B B', of sheet metal, adapted to telescope together, the section B' 25 passing within the section B.

C represents a bolt placed at each corner of the body, and extending through both sections thereof, said bolts being provided on one end, outside of the body, with a thumb-nut, C', to 30 regulate the amount of extension of the sections to give the desired amount of interior space.

D D' represent a double top and bottom, respectively, to the box, inside of the bolts C, 35 in order to give an unbroken rectangular shape to the interior thereof, the said double top and bottom being secured to the section B, while the small supplemental plates d d' are secured to the section B', to slide close to the said top 40 and bottom plates, D D', and adapted to serve as extensions to the said top and bottom when the sections B B' are extended.

E is a casting secured to the lower side of the body, having a handle, E', for a purpose 45 hereinafter explained, and F is a casting secured to the upper side of the body, having a loop, f, in the upper part, to which is secured the lower end of a spring-balance, G, adapted to normally hold the device raised out of the 50 way. The said spring-balance is of any ordinary or preferred construction—as, for in-

stance, a spring-roller having a band or strap to be rolled thereon, to the lower end of which strap is attached the indicator-body, in the manner described.

The object is to provide means whereby, when released, the body of the indicator will be drawn up to the limit of motion thereof, out of the way.

H H are guide-rods passing through perforated ears h h on the sides of the box, and adapted to guide the vertical motion of the said box and prevent all lateral motion thereof. The opposite sides of the box are provided with openings I I, through which is exhibited 65 the name of the station at which the train or car will next stop.

K represents the label or slip of sheet metal having the name of a station on each side, said label being adapted to be inserted into the box 70 through the open end L of the box, the opposite end being closed and shaped to represent the protruding ends of the said labels, in order to make the appearance of the device symmetrical.

M is a small ridge or edge formed at the lower side of the opening L, adapted to enter a small recess or notch, l, in the lower side of the outer end of the labels and prevent the same from slipping out of the body by the 80 jolting of the car while in motion.

The labels are so arranged in the box that when a station has been passed the conductor, drawing the indicator down within reach, removes the label from one side of the box and 85 places it at the other without turning it, and the name of the next station is indicated on both sides of the box. The manner of arranging these labels and the names thereon is very simple—namely, the name of the first station 90 and the name of the succeeding station are placed on opposite sides of the same label; the names of the second and third stations are placed on opposite sides of the second label; the names of the third and fourth stations are 95 placed on opposite sides of the third label, and so on. Thus when the first label is drawn out of the body and placed in the other end thereof the name on the opposite side of the said first label will be exposed, (being at the 100 opposite end of the box,) and the name of the second station, which is on one side of the sec-

ond label, will be allowed to show, thus exhibiting the name of the second station at both ends of the box.

It will be seen from the above that my improved indicator is very simple of construction and operation, and it is also a very satisfactory indicator, as, being hung in the center of the car, it is visible from any part thereof, and the name of the succeeding station is exhibited on both sides thereof by simply changing the position of one label.

Having now described my invention, what I claim, and desire to secure by Letters Patent, is—

- 15 1. The indicator having the body formed of two or more telescoping sections and having the sides thereof open to show the name on the interior label or slip, substantially as described, for the purpose set forth.
- 20 2. An indicator having the body formed of the telescoping sections B B', and the through-bolts C, provided with thumb-nuts on the outside of the box to regulate the interior space of the said body, substantially as described, for 25 the purpose set forth.
- 30 3. An indicator having the body A, comprising the telescoping sections B B', bolts C, to hold the said sections at the proper extension, and the false or double top and bottom plates each being formed of two sections adapted to slide one over the other to present an unbroken rectangular shape within the said body, substantially as described.
- 35 4. The indicator having the body comprising the telescoping sections B B', having openings in the sides to show the name of the sta-

tion, and being open at one end to allow the insertion of the labels bearing the said names, and closed at the other end, substantially as described.

5. The combination, in an indicator, of the body A, to contain the names of the stations, loop on the upper side, handle on the lower side, guide-rods on which the said body slides to direct the motion of the body, and means, 45 substantially as described, whereby the same when released is drawn up out of the way, substantially as and for the purpose set forth.

6. In an indicator, the body A, to contain the names of the stations, the guide-rods on 50 which the said body slides to direct the motion thereof, and spring-actuated means connecting with the body to draw the latter up when released, as set forth.

7. The indicator having the body A, provided with the openings I I in the opposite sides, and the opening L in one end, having a ledge or ridge, M, at the lower side, combined with the labels K, having a small recess or notch, l, in the lower edge to receive the said ridge when the label is in place and prevent the same from being jarred out of position, substantially as described, for the purpose set forth.

In testimony that I claim the foregoing as 65 my own I have hereto affixed my signature in presence of two witnesses.

CHRISTIAN OLSEN.
